PORTABLE ILLUMINABLE DIRECTION SIGN

Samuel G. Costas, Fond du Lac, Wis.

Application February 12, 1952, Serial No. 18,497

Term of patent 14 years

(Cl. D72—1)

To all whom it may concern:

Be it known that I, Samuel G. Costas, a citizen of the United States of America, residing at Fond du Lac, in the county of Fond du Lac and State of Wisconsin, have invented a new, original, and ornamental Design for a Portable Illuminable Direction Sign, of which the following is a specification, reference being had to the accompanying drawing, forming part thereof.

In the drawing:

Figure 1 is a three-quarter front perspective view of a portable illuminable direction sign, showing my new design;

Figure 2 is a rear elevational view;

Figure 3 is an end elevational view; and
Figure 4 is a bottom view in plan.

I claim:

The ornamental design for a portable illuminable direction sign, as shown.

SAMUEL G. COSTAS.
